UNITED STATES PATENT OFFICE.

EUGENE PEARL, OF PASSAIC, NEW JERSEY.

DESIGN FOR A PENCIL-CASE.

No. 39,559.

Specification for Design.

Patented Sept. 22, 1908.

Application filed May 9, 1908. Serial No. 431,990. Term of patent 7 years.

To all whom it may concern:

Be it known that I, EUGENE PEARL, a citizen of the United States, residing at Passaic, in the county of Passaic and State of New Jersey, have invented a new, original, and ornamental Design for a Pencil-Case, of which the following is a specification, reference being had to the accompanying drawings, forming part thereof, in which—

Figure 1, is a plan view of a pencil case, showing my new design, and Fig. 2, is a side view thereof.

When viewed in plan as in Fig. 1, the gen-

eral outline of the case is rectangular. The corners of the rectangle are shaped to give one end thereof a more or less rounded appearance, and the other end a tapered form. About midway of the length, rounded projections are formed on opposite sides.

I claim

The ornamental design for a pencil case as shown and described.

EUGENE PEARL.
